UNITED STATES PATENT OFFICE.

WILLIAM SEVERNS, OF CHICAGO, ILLINOIS.

MOP-CUTTING MACHINE.

Application filed August 17, 1921. Serial No. 493,013.

To all whom it may concern:

Be it known that I, WILLIAM SEVERNS, a citizen of the United States, and a resident of the city of Chicago, in the county of Cook and State of Illinois, have invented certain new and useful Improvements in a Mop-Cutting Machine; and I do hereby declare that the following is a full, clear, and exact description of the same, reference being had 10 to the accompanying drawings, and to the numerals of reference marked thereon, which form a part of this specification.

This invention relates to improvements in machines for making mops and is especially 15 adapted for use in connection with the manufacture of a mop and the process of making the same such as is shown and described in my copending application for U. S. Letters Patent on "process of making 20 mops", filed August 17th, 1921, Serial No. 493,014. This machine is adapted to be used with the frame shown in the copending application herein referred to, but it will be understood that it is adapted to be used with 25 other machines for making mops or the like and is not confined to the particular process as disclosed in the copending application.

One of the objects of this invention is the provision of a machine adapted to properly 20 sever the strands of a skein of hank or yarn or the like which has been wound upon a frame in regular order and which will sever this yarn in such a manner as to form it into strands of equal length to constitute the body 35 of a mop.

Another object of this invention is the provision of a machine which has cutting knives adapted to sever such a skein or hank of yarn into strands of equal length to form 40 a mop, a cutting knife being mounted upon each side of the machine and both coacting together to complete the cutting of the strands in one operation of the machine.

Still another important object of the invention is the provision of a machine adapted 45 to cut yarns into lengths to form mops which is adapted to be used with a frame upon which the yarn is wound and which is adjustable so that the knives may be adjusted to conform to any particular size of 50 frame adapted to make any size or weight of mop as required.

Another and further important object of the invention is the provision of a machine for cutting mops which shall act to cut a 55 number of the mops into shape in a very short space of time, thereby eliminating the cost of labor which has heretofore been necessary in cutting and assembling the strands.

Other and further important objects of 60 the invention will be apparent from the disclosures in the accompanying drawings and the following specification.

The invention (in a preferred form) is illustrated in the drawings and hereafter 65 more fully described.

On the drawings:

Figure 1 is a top plan view of the machine as embodied in this invention.

Figure 2 is a sectional view taken on line 70 2-2 of Figure 1, looking in the direction indicated by the arrows.

Figure 3 is a plan view of the frame upon which the strand of yarn is wound preliminarily to forming the mop. 75

Figure 4 is a sectional view taken on the line 4-4 of Figure 3.

Figure 5 is an enlarged detail view showing the construction of one of the rotary cutting knives and the driving means therefor. 80

Figure 6 is a similar view of one of the rotary cutting knives showing the means by which its position relative to the machine and to the other knife is adjusted. 85

As shown on the drawings:

The machine comprises a frame or base 10 having supporting legs 12 and provided at its top with a table or platform 14 upon which the work is placed to be operated 90 upon. Mounted upon a shaft 16 extending transversely of the machine are a pair of pulleys 17 and 19, one for driving and the other a loose or idler pulley connected by a belt to any convenient source of power. 95 Slidably mounted on the shaft 16 and keyed by suitable keys or feathers acting in the keyway 21 so as to be rotatable therewith is a beveled gear 18 mounted in bearings integral with and projecting from a downwardly extending support 20 which is held in position by the table 14 and the shaft 16. A similar support 50 is provided for a gear 38 likewise fixed on and driven by the 100

2

shaft 16, but which is not movable relative to the table 14. The support 20 is slidable in a slot 22 in the table 14 and both supports may be made so if desired. Mounted in each 5 of these supports 20 and 50 in suitable bearings is a vertical shaft 24 having at its upper end a circular cutting knife 26, and fixed on the lower end of each vertical shaft 24 is a beveled gear 28 adapted to co-operate 10 with and be driven by the beveled gears 18 and 38 on the shaft 16. Integral with the supporting member 20 is an outwardly extending lug 30 having a hole therethrough, as shown in Figure 5, and this hole is internally threaded to correspond with threads 15 on an adjusting rod 32 extending transversely of the machine, and having its ends mounted in bearings in the frame, as shown in Figure 2. This rod 32 is provided with 20 right-hand threads on one side thereof and, if desired, left-hand threads on the other side so that the rotation thereof by means of a wheel or handle 34 will tend to cause the approach or recession of one or both of 25 the members 20 and 50 to and from each other, this movement of course including their attached gears 18 and 38 and the circular knives 26 driven thereby. Adapted to co-operate with the circular knives 26 is a 30 frame 40 upon which a strand of yarn is wound in regular layers to form a mop, the process of winding this yarn and forming a mop being described in my co-pending application hereinbefore referred to.

35 A strip or support 42 is sewed to the strands of yarn after they have been wound on the frame 40, as best shown in Figure 3, and the frame with the yarn thereon is then passed through the machine and the circular knives 16 act to sever the yarn at both 40 sides of the frame, suitable depressions or grooves being provided in the frame, as shown at 44 in Figure 4, to provide for the edges of the knives and their proper coaction with the frame 40. In this way the 45 yarn on the frame is severed in a neat, quick and efficient manner and the edges are cut so as to correspond very closely to each other when the swatch so formed is folded over to 50 form the finished mop.

The frame 40 may be fed through the machine either by hand or with a manually regulated mechanical feed if desired, or the feed may be entirely automatic, depending 55 upon the nature of the operation.

The operation is as follows:

After the yarn 41 has been wound upon the frame 40 by any suitable means (the preferred form being shown in my copending 60 application for U. S. Letters Patent on "machine for making mops, filed August 17th, 1921, Serial No. 493,014, and the strip or binder 42 sewed thereon, the frame with the attached yarn is then in the condition as

shown in Figure 4, and it is placed upon the 65 table 14 of the machine and passed between the rotating knives 26, by which the yarn is severed all along both of the longitudinal edges of the frame 40, the edges of the knives 26 working in the grooves 44 in the 70 sides of the frame. This acts to sever the strands of yarn very neatly and completely, allowing the swatch so formed to be taken as a whole out of the frame 40 which may then be used for the preparation of another 75 mop. The swatch is then doubled into the form of a mop, as shown in my copending application hereinbefore referred to.

It will be evident that the frames 40 may be made of any size for the construction of 80 mops of any desired weight or size, and that the construction of these frames allowing the mechanical winding thereon of a sufficient quantity of yarn is a much more efficient operation than that formerly in use 85 whereby an approximate quantity of yarn was taken by hand from a stack of the same, weighed upon a scale and then manually distributed over a strip to which it was afterwards sewed. In the sewing the edges were 90 always left uneven and the product had to be cut and trimmed with a resulting loss of material. All of these operations being manual consequently involved an expenditure of a good deal of time and expense, and 95 also considerable waste.

The operation of this machine will tend to form a mop in a much shorter space of 100 time than has hitherto been required and consequently will turn out a much cheaper product and one which is cut more neatly and therefore more efficient in its operation, inasmuch as the length of all the strands is exactly the same.

I am aware that many changes may be 105 made and numerous details of construction varied without departing from the principles of this invention, and I therefore do not purpose limiting the patent granted hereon otherwise than necessitated by the prior art.

I claim as my invention:

1. In apparatus for making mops, a frame 110 having parallel grooved sides upon which the yarn is wound, in combination with spaced rotary cutting elements between which the frame is passed with the grooved sides adjacent the cutting elements.

2. In apparatus for making mops, a frame 115 having parallel grooved sides upon which the yarn is wound, in combination with adjustably spaced cutting elements between which the frame is passed with the grooved sides adjacent the cutting elements, and means for simultaneously rotating said cutting elements.

3. In apparatus for making mops, a support, a pair of spaced rotary cutting elements mounted in said support, means for 120

relatively adjusting said cutting elements, a common drive shaft geared to both cutting elements, in combination with a frame having parallel grooved sides upon which the yarn is wound and adapted to be passed between said cutting elements with the grooved sides adjacent said elements.

In testimony whereof I have hereunto subscribed my name in the presence of two subscribing witnesses:

WILLIAM SEVERNS.
